US0D1044174S

(12) **United States Design Patent** (10) **Patent No.:** **US D1,044,174 S**
(45) **Date of Patent:** **** Sep. 24, 2024**

(54) **COMBINED LAUNDRY TREATING APPLIANCE AND PEDESTAL**

5,628,430 A 5/1997 Barbe
5,782,109 A 7/1998 Spriggs
6,109,480 A 8/2000 Monsrud

(71) Applicant: **WHIRLPOOL CORPORATION**,
Benton Harbor, MI (US)

(Continued)

(72) Inventors: **Daniel Polonsky**, Stevensville, MI
(US); **Anna C. Schelling**, Stevensville,
MI (US)

AU 2008202222 12/2008
BR 202013015525 U2 8/2015

(Continued)

(73) Assignee: **Whirlpool Corporation**, Benton
Harbor, MI (US)

FOREIGN PATENT DOCUMENTS

(**) Term: **15 Years**

(21) Appl. No.: **29/752,888**

(22) Filed: **Sep. 29, 2020**

Related U.S. Application Data

(62) Division of application No. 29/708,461, filed on Oct. 7, 2019, now Pat. No. Des. 900,418, which is a division of application No. 29/630,487, filed on Dec. 21, 2017, now Pat. No. Des. 865,306.

(57) **CLAIM**

The ornamental design for a combined laundry treating appliance and pedestal, as shown and described.

DESCRIPTION

FIG. 1 is a top perspective view of a combined laundry treating appliance and pedestal;

FIG. 2 is a front view of the combined laundry treating appliance and pedestal of FIG. 1;

FIG. 3 is a left side view of the combined laundry treating appliance and pedestal of FIG. 1; and,

FIG. 4 is a right side view of the combined laundry treating appliance and pedestal of FIG. 1.

Portions of the drawings shown in broken lines illustrate portions of the combined laundry treating appliance and pedestal that form no part of the claimed design.

1 Claim, 4 Drawing Sheets
